FIG. 4

FIGURE 1 is an exploded perspective view of a butter dish or similar article showing my new design;
FIGURE 2 is a top plan view of the same;
FIGURE 3 is a bottom plan view of the same;
FIGURE 4 is a side elevational view of the same;
FIGURE 5 is a right end view of the same; and
FIGURE 6 is a left end view of the same.

It is understood that apart from a narrow peripheral border, the pebbled surface as shown is continuous over the entire uppermost surface of the tray member, as indicated.

The essential features of the design are shown in full lines in the drawing, the broken line showing of a cover being omitted from FIGURES 2 through 6 for convenience of illustration.

This is a continuation-in-part of my earlier application, Serial No. D.69,122, filed March 7, 1962, and now abandoned.

I claim:
The ornamental design for a butter dish or similar article, as shown and described.
